UNITED STATES PATENT OFFICE.

HUGH M. ALBEE, OF ORANGE, MASSACHUSETTS, ASSIGNOR TO THE LEAVITT MACHINE COMPANY, OF ORANGE, MASSACHUSETTS.

FACING TOOL FOR DRESSING VALVE SEATS.

Application filed July 24, 1924. Serial No. 727,951.

To all whom it may concern:

Be it known that I, HUGH M. ALBEE, a citizen of the United States, residing at Orange, in the county of Franklin and State 5 of Massachusetts, have invented certain new and useful Improvements in Facing Tools for Dressing Valve Seats; and I do hereby declare the following to be a full, clear, and exact description of the invention, such as 10 will enable others skilled in the art to which it appertains to make and use the same.

The invention relates to certain useful improvements in facing tools for dressing valve seats, applicable more particularly to gate 15 valves, and has for its object to provide a cutter-bar of the same general type as illustrated in Patent No. 1,227,515, dated May 22, 1917, on the application of Williams, Dexter and Smith, with certain ancillary 20 features of adjustment which will insure the centering of the cutter proper with respect to the valve seat to be dressed, as will be more particularly pointed out in the following specification, predicated on the accompanying drawings, in which:—

Fig. 1 is a front elevation of the cutter-bar.

Fig. 2 is a rear elevation of the same.

Fig. 3 is a partial front elevation showing 30 a modified form of the invention.

Fig. 4 is a side elevation, partly in section, of a gate valve casing with the cutter-bar and cutter in operative relation, to effect the dressing of one of the seats.

Fig. 5 is an enlarged front elevation of the 35 lower part of the cutter-bar, with the face plate of the slide removed.

Fig. 6 is a horizontal section on line 6—6 of Fig. 5.

Referring to the drawings, Figs. 1, 2, 5 and 6, 1—1 indicate the side members of a flat frame, provided with a connecting yoke 2 at the bottom, which is connected with the side members 1 by scarf joints 3, the 45 upper portion of the frame being bridged by a generally rectangular frame 4' connected to the members 1—1 by a suitable joint 5, the several elements being secured together by machine screws. The inner edges 50 of the side members 1—1 are provided with grooves in which operate a two-piece slide, comprising a lower member 3 and an upper member 5, the said members being adjustably connected together by means of a bolt 55 7 engaging a longitudinal screw-threaded

bore 7' in member 3, the head 8 of the bolt fitting in a rectangular recess 6 in the member 5, so that when the bolt 7 is turned by a pin engaging radial holes in the head 8 thereof, the two members of the slide will 60 be adjusted toward or from each other. The lower end of the member 3 is provided with a laterally extending generally arcuate jaw or abutment 4 on one face, which co-operates with a similarly shaped fixed jaw or abutment 9 on the corresponding face of the lower end 2 of the cutter bar.

Slidably mounted in the cutter bar frame, below the slide 3, is a second slide 10, which is preferably formed as a generally rectangular hollow casting having a face plate 11, the lateral edges of the slide 10 overlying the inner edges of the bars 1 on both sides to permit the slide to be adjusted longitudinally of the frame. Mounted centrally within the slide 10 is a pivot pin 14, having a rounded forward head to engage a concave recess in the rear face of a cutting tool A, generally similar to that shown in the patent aforesaid, said pivot pin 14 being capable 80 of adjustment longitudinally of its axis and at right angles to the movement of the slide 10. Preferably the pin is supported in its movements in a cylindrical sleeve 13, integrally formed with a face plate 12 secured 85 to the main face plate 11 of the slide 10. The inner end of the pivot pin 14 is screw-threaded and engages the interiorly screw-threaded hub of a worm 18 which is journaled in aligning openings in the front and back 90 plates of the slide 10, so that when said worm 18 is rotated in one direction or the other, the pin 14 will be moved in or out with respect to the slide 10, the pin being prevented from rotating by means of a key 16 95 which engages slots 15 in the pin and 17 in the slide.

The upper slide, comprising the connected members 3 and 5, and the lower slide 10, are adapted to be adjusted axially of the frame in which they are mounted, by means of a differential screw spindle mounted for rotatory motion in the frame and held against longitudinal movement in the frame, said screw comprising an upper reduced section 105 20 projecting beyond the upper end of the frame member 4', and provided with a wrench head, and an intermediate screw-threaded portion 21 of larger diameter, the shoulder portion of which abuts the lower 110

face of the frame member 4', said intermediate section being provided with screw threads engaging a similarly threaded bore 5' in one side of the slide member 5. The 5 lower end 22 of the screw-threaded spindle is provided with screw threads of smaller pitch, which engage threaded openings in vertical alignment in the slide 10, the pitch of the threads on the respective spindle sections 21 and 22 preferably having a ratio of 2 to 1, so that the movement of the upper slide will always be twice as great as that of the lower slide.

Journaled in the frame of the cutter-bar, 15 on the side opposite the screw spindle aforesaid, is an operating shaft or spindle 30, provided with a wrench head on its upper end, with its lower end supported in a recess in the bottom section 2 of the frame, 20 the spindle being held against longitudinal movement by a collar 31 which abuts the lower edge of the frame member 4'. The lower end of the spindle 30 is flattened for a considerable distance on one side, as at 32, 25 to provide a sliding fit with the hub 20 of a worm pinion 19, mounted in the slide 10, as illustrated in Figs. 5 and 6, which pinion meshes with the worm 18 which is in engagement with the pivot pin 14, as hereinbefore described. It will be noted that the pinion 19 is held against longitudinal movement within the slide 10, by the engagement of the upper and lower ends of the hub sections 20 with the top and bottom 30 walls of the slide 10, and that the lower end of the spindle, with the flattened face 32 engaging the correspondingly shaped opening through the hub of the pinion 19, admits of the pinion sliding freely on the spindle 32, as the slide is adjusted up and down in the frame, without in any way interfering with the positive driving connection between the spindle 30 and the pinion. In fact this particular form of connection between the lower end of the spindle and the pinion affords a simpler and more effective driving coupling than would an ordinary spline or feather.

As heretofore indicated the cutter-bar, as described, like that of the patent aforesaid, is designed as a centering support for the cutting tool A, the cutter-bar being adapted to be positioned and clamped within the interior of the valve seat or seat ring, opposite the valve seat or ring to be resurfaced, as indicated in Fig. 4. This clamping operation is effected by positioning the cutter-bar so that the lower jaw or abutment 9 engages the inner surface of the seat ring, after which the upper slide is adjusted by turning the screw spindle 20, to elevate the upper slide until the jaw or abutment 4 is forced into firm clamping engagement with the upper surface of the seat ring. The operation of the screw

spindle to elevate the upper slide also elevates the lower slide 10, the movement of the latter being only half that of the upper slide, the object of this differential movement between the slides being to bring the 70 pivot pin 14 in the axial center of the valve seat or seat ring, which would ordinarily position the pivot pin in proper relation to center the rotary cutting tool or head of the cutter A, with respect to the seat ring to be dressed or resurfaced. It frequently happens however that the two seat rings or valve seats of a valve of this character are not in axial alignment, so that the centering of the pivot pin 14 with respect to the seat ring S' (see Fig. 4), would not properly center the head of the cutter A with respect to the seat ring S, which would prevent the latter being properly dressed or resurfaced, because of the fact that the cutting edges or knives on the rotary head of the cutter A would not engage the whole of the face of the valve seat S. The instant invention is designed to obviate this difficulty and provide means for accurately centering the pivot pin 14 with respect to the seat to be dressed, instead of centering said pin with respect to the ring or seat in which the cutter-bar is clamped. This result is brought about by adjusting the members 3 and 5 of the upper slide relatively to each other, or in other words adjusting the member 3 of the upper slide independently of the lower slide 10, which carries the pivot pin 14. The threaded portions 21 and 22 of the screw spindle which simultaneously operate the upper and lower slides passes loosely through a longitudinal bore 3' in the member 3 of the upper slide so that the latter may be raised and lowered relatively to the upper member 5 of said upper slide by operating the screw 7 in the proper direction, by means of a pin inserted successively in the holes of the head 8 of the screw and turning the screw to the right or left. By this means the member 3 of the upper slide may be so adjusted relatively to the lower slide 10 that, when the cutter-bar is firmly clamped in position in one of the seat rings, as S', the pivot pin 14 will be in exact axial alignment with the center of the cutter head on the cutter A. If, for example, the central axis of the ring S, which is the ring to be dressed, is lower than that of the central axis of the ring S', in which the cutter-bar is to be clamped, the lower member 3 of the upper slide will be raised by an amount equal to one-half the lineal distance between the central axes of the rings S and S', so that when the jaws 4 and 9 of the cutter-bar are forced into clamping engagement with the ring S', by operating the screw spindle 20, the lower slide 10 will be elevated and the pivot pin 14 will be in exact axial align- 130

ment with the geometrical center of the ring S. On the other hand, if the center of the ring S is higher than that of the ring S', the lower member 3 of the upper slide 5 will be moved downwardly by the screw 7 a distance equal to one-half the distance between the centers, after which the operation of the screw spindle to clamp the cutter-bar into position, will move the lower slide 10 just sufficiently to bring the pivot pin 14 into axial alignment with the center of the cutter head. It will therefore be seen that the device is adapted to position the pivot pin 14 exactly in axial alignment with the 15 center of the head of the cutter disc on the cutter A, when said cutter head is in proper relation to the face of the valve seat to be dressed, irrespective of the relative positions of the longitudinal axes or geometrical centers of the respective valve seats. 20

In Fig. 3 a modification of the means for relatively adjusting the two members of the upper slide is shown, this particular form of adjustment being desirable in relatively 25 large cutter-bars to effect a rapid adjustment. It will be noted that the adjusting screw 7^a connecting the upper member 5^a with the lower member 3^a, is a double screw, the threads on the respective ends being opposite in direction and engaging screw-threaded sockets 6^a in the upper member 5^a and 3^b in the lower member 3^a, so that when the screw is turned by a pin engaging the radial holes in the head 8^a, the slide members 3^a and 5^a will be rapidly adjusted toward or from each other as the case may be. This specific form of adjustment between the slides is an obvious variant of that shown in the preceding figures and, as indicated, 30 is employed in tools of this character of relatively large size in order to facilitate the adjustment of the two members of the upper slide.

What I claim is:

1. A cutter-bar for gate-valve seat dressing tools having a plurality of relatively movable holding elements for engaging a valve-casing and holding the cutter-bar to said casing, a pivot element movable longitudinally of the bar, means carried by the cutter-bar to simultaneously effect relative movement between said holding elements and relative movement of a predetermined ratio between the pivot element and one of said holding elements, and means for adjusting the last mentioned holding element independently of the pivot element.

2. A cutter-bar for gate-valve seat dressing tools having a plurality of relatively movable holding elements for engaging a valve-casing and holding the cutter-bar to said casing, a pivot element movable longitudinally of the bar, means carried by the cutter-bar to simultaneously effect relative movement between said holding elements

and relative movement at a two-to-one ratio between the pivot element and one of said holding elements, and means for adjusting the last mentioned holding element independently of the pivot element.

3. A cutter bar for gate-valve seat dressing tools having at different points in the length thereof a pair of relatively movable holding elements for engaging the interior of a valve-casing and holding the cutter-bar to said casing, one of which parts is a fixed element and the other of which is carried by a slide movable lengthwise of said cutter-bar, a pivot element carried by said cutter-bar for co-operation with a cutter, means for imparting differential feed movements to said slide and pivot element lengthwise of the cutter-bar, and means for adjusting the movable holding element independently of the pivot element.

4. A cutter-bar for gate-valve seat dressing tools having a plurality of relatively movable holding elements for engaging the interior of a valve-casing and holding the cutter-bar to said casing, a pivot element carried by said cutter-bar for co-operation with a cutter, means for imparting differential feed movements to one of said holding elements and said pivot elements crosswise of the axis of the pivot element, and means for adjusting the last mentioned holding element independently of the pivot element.

5. A cutter-bar for gate-valve seat dressing tools having at different points in the length thereof a pair of relatively movable holding elements for engaging the interior of a valve-casing and holding the cutter-bar to said casing, one of which elements is fixed and the other of which is carried by a slide movable lengthwise of said cutter-bar, a second slide movable lengthwise of said cutter-bar, a pivot element carried by said second slide for co-operation with a cutter, means for imparting differential feed movements to said slides, and means for adjusting the movable holding element independently of the pivot carrying slide.

6. A cutter-bar for gate-valve seat dressing tools having at different points in the length thereof a pair of relatively movable holding elements for engaging the interior of a valve-casing and holding the cutter-bar to said casing, one of which elements is fixed and the other of which is carried by a slide movable lengthwise of said cutter-bar, a second slide disposed between said holding elements and also movable lengthwise of said cutter-bar, a pivot element carried by said second slide for co-operation with a cutter, means for imparting differential feed movements to said slides, and means for adjusting the movable holding element independently of the pivot carrying slide.

7. A cutter-bar for gate-valve seat dressing tools having a plurality of holding ele-

ments for engaging the interior of a valve-casing and holding the cutter-bar to said casing, one of said holding elements being movable on said cutter-bar, a pivot element 5 carried by said cutter-bar and having its axis crosswise thereof for co-operation with a cutter, means for shifting said movable holding element and the pivot element relatively to each other transversely of the axis 10 of said pivot element, and means for adjusting the movable holding element independently of the pivot element.

8. A cutter-bar for gate-valve seat dressing tools having a plurality of holding elements for engaging the interior of a valve-casing and holding the cutter-bar to said casing, one of said holding elements being movable on said cutter-bar, a pivot element carried by said cutter-bar and having its axis crosswise thereof for co-operation with a cutter, means for shifting said movable holding element and the pivot element relatively to each other transversely of the axis of said pivot element, said means including a common operating device, and means for adjusting the movable holding element independently of the pivot element.

9. A cutter-bar for gate-valve seat dressing tools having a slide thereon including an element for holding said cutter-bar to a valve-casing, a centering slide movable lengthwise of said cutter-bar, means carried by the cutter-bar for simultaneously im-

parting to said slides proportional movements, and means for adjusting the holding slide independently of the centering slide. 35

10. A cutter-bar for gate-valve seat dressing tools having a fixed holding jaw, a slide carrying a complementary holding jaw, a slide intermediate said jaws carrying a 40 tool centering pivot, means for simultaneously effecting differential movements of said slides, and means for adjusting the jaw carrying slide independently of the pivot carrying slide. 45

11. A cutter-bar for gate-valve seat dressing tools having a fixed holding jaw, a slide carrying a complementary holding jaw, said slide comprising two sections relatively adjustable longitudinally of the bar, a slide 50 intermediate said jaws carrying a tool centering pivot, and means for simultaneously effecting differential movements of said slides.

12. A cutter-bar for gate-valve seat dressing tools having a fixed holding jaw, a slide carrying a complementary holding jaw, said slide comprising an upper section, a lower section and a screw connecting said sections to adjust the latter toward and from each other, a slide intermediate said jaws carrying a tool centering pivot, and means for simultaneously effecting differential movements of said slides. 55

In testimony whereof I affix my signature.
HUGH M. ALBEE.
